UNITED STATES PATENT OFFICE.

PAUL A. JOHNSON, OF GRAND HAVEN, MICHIGAN, ASSIGNOR OF ONE-HALF TO ALVIN E. JACOBSON, OF GRAND HAVEN, MICHIGAN.

TOILET-SEAT HINGE.

Application filed May 7, 1928. Serial No. 275,686.

This invention relates to hinges for use on toilet seats and is primarily concerned with a simple and very practical hinge construction economical to manufacture, readily installed and assembled and which when assembled operates effectively and is not liable to get out of order.

An understanding of the invention whereby these ends are attained may be had from the following description taken in connection with the accompanying drawing, in which,

Fig. 1 is a perspective view illustrating a toilet seat and cover mounted on a bowl, the hinge of my invention being used therewith.

Fig. 2 is a fragmentary enlarged section showing the assembled hinge construction and how it is applied and attached to the seat and cover.

Fig. 3 is a perspective view showing the several parts of the hinge separated from each other, and,

Fig. 4 is a fragmentary enlarged horizontal section substantially on the plane of line 4-4 of Fig. 2.

Like reference characters refer to like parts in the different figures of the drawing.

The toilet bowl 1 is of any usual standard construction, at its upper end being provided with a rearwardly extending horizontal ledge 2. Spaced apart openings are made downwardly through the ledge for the passage of bolts or rods 3, threaded at their lower ends and equipped at their upper ends with heads 4 which are enlarged at their portions to provide flanges 5 adapted to bear against the upper side of the ledge 2. Nuts 6 threaded on to the lower ends of the rods 3 secure the rods with the attached heads 4 permanently to said ledge 2. Each of the heads 4 is formed at one side with a horizontal cylindrical opening 7 which extends nearly through the head; and when the bolts 3 with said attached heads 4 are properly secured to the ledge 2, the openings are at the inner sides of the heads and in horizontal alignment with each other.

The hinge construction includes an irregularly shaped member comprising a horizontal cylindrical rod 8 exteriorly threaded, at the outer end of which an arm 9 extends forwardly at right angles to the axis of the rod 8, and which, at its outer end, is provided with an integral outwardly extending cylindrical portion 10 screw threaded at its outer side and interiorly bored from its outer end

to make an opening 11 extending substantially to the arm 9, there being an opening in the arm 9 at the bottom of the opening 11 of considerably smaller size.

One of these irregularly shaped members, as described, is located and secured to the toilet seat 12 at each side thereof adjacent its rear end. Suitable horizontal openings are bored in the opposite sides of the seat and the rods 8 threaded therein until arms 9 come against the sides of the seat and are positioned substantially horizontal and extend in a forward direction. Screws 13 are then passed through the openings 11 and through the smaller openings in the arm 9 which is of a size to freely pass the shank of the screw but not the head. The screws 13 are driven into the side edges of the toilet seat, as shown in Fig. 4. In this manner one of these members is permanently secured at each side and near the rear end of the seat.

A bar 14 of metal passes over the extension 10, it having an opening 15 adjacent its lower end shaped to fit the exterior of arm 9 whereby the bar may be brought into immediate engagement with the edge of the seat. Bar 14 at its upper end has an enlarged head 16 in which an opening 17 is made at the inner side for the reception of one end of a pivot pin 18, the opposite end portion of the pin 18 extending into the seat cover 19. The seat cover accordingly is mounted on the two pins 18, as shown in Fig. 2, which at their outer ends are rotatably received in recesses 17. In order to permanently secure the bars 14 in place nuts 20 of cylindrical form are threaded on to the extensions 10 to lock the bar 14 in place.

The exterior diameter of the nuts 20 is slightly less than the interior diameter of the cylindrical recesses 7 in the heads 4. The hinge construction comprising the threaded rod 8, arm 9 and the extension 10, together with the bar 14 and the locking nut 20 may be assembled at each side and at the rear end of the seat and seat cover, and thereafter the heads 4 with their depending rods 3 placed over the nuts 20, both rods then being passed downwardly through the openings in the ledge 2 and the whole secured in place between nuts 6 previously described.

It is evident from the foregoing that with this hinge the seat cover 19 alone may be turned back and forth about the axes of the pins 18, or both the cover and seat may be

turned back and forth about the axes of the extensions 10 described, the nuts 20 operating as bearings in the cylindrical recesses 7.

This construction is of few parts, all easily 5 manufactured and very quickly and easily assembled with the seat and seat cover. When assembled the double screw connection of rod 8 and the screw 13 affords a very secure and permanent connection and one which does 10 not readily work loose. The invention has proved very practical and serviceable. It is defined in the appended claims and is to be considered comprehensive of all forms of structure coming within the scope thereof.

15 I claim:

1. A hinge comprising, a vertical post having a head at the upper end thereof, said head having a horizontal cylindrical opening in one side, a hinge member comprising a 20 threaded rod, an arm projecting laterally from one end of the rod and a threaded extension having an axis paralleling the axis of the rod extending from said arm, said extension having a cylindrical opening substantially therethrough, a bar of metal having an opening at one end to pass over said arm and a cylindrical nut threaded on to said extension and against the outer side of said bar, said nut being received within the 25 opening in said head and said bar extending upwardly above the arm and formed at its upper end with a head having a horizontal opening at its inner side.

2. In combination a support, two spaced 30 apart members attached to and extending above said support, each member having a head at its upper end formed with a cylindrical horizontal opening at its inner side, a seat located between said heads, a hinge 35 member at each side of the seat including a threaded rod screwed into the seat and having a forwardly extending arm at its outer end bearing against an edge of the seat, said arm being provided at its forward end with a 40 horizontal outward extension threaded at its outer side and having a cylindrical opening

lengthwise thereof, a screw passing into said opening and through the end of said arm into the seat, a bar of flat metal having an opening to receive said arm located against each edge of the seat, a cylindrical nut threaded on to the end of each extension, said nuts being located in the openings in the heads of said supports, the bars extending upwardly above said arms, and a seat cover disposed between the upper ends of the arms and pivotally connected thereto to turn about a horizontal axis. 50

3. In combination, a horizontal support, two spaced apart members connected to and extending above said support, a seat located between said members, a hinge member connected at each side edge of the seat near its rear end, each having an arm bearing against a side edge of the seat and a threaded extension projected outwardly from the arm, a bar located over each arm, a nut threaded on to each extension for securing said bar against the adjacent side edge of the seat, a head on each of said members having a cylindrical opening receiving said nuts and said bars extending upwardly above said seat, and a seat cover located between the upper ends of the bars and pivotally connected thereto to turn about a horizontal axis. 60

4. In combination a seat, a hinge member connected to said seat at each side thereof and near its rear end including a horizontal arm lying against the outer edge of the seat and a threaded extension projecting outwardly from the arm, a bar of metal having an opening to receive said arm located against each side of the edge of the seat and extending upwardly above the same, a nut threaded on to each of said extensions to secure the bars in place, and a seat cover located between the upper ends of said bars and pivotally connected therewith to turn about a horizontal axis. 70

In testimony whereof I affix my signature.

PAUL A. JOHNSON.
